UNITED STATES PATENT OFFICE.

JOHN HASSELBRING, OF BROOKLYN, NEW YORK.

DESIGN FOR A NAPKIN-RING.

SPECIFICATION forming part of Design No. 25,637, dated June 16, 1896.

Application filed May 9, 1896. Serial No. 590,949. Term of patent 31 years.

To all whom it may concern:

Be it known that I, JOHN HASSELBRING, of Brooklyn, in the county of Kings and State of New York, have invented and produced a new and original Design for a Napkin-Ring, of which the following is a full, clear, and exact description.

Reference is to be had to the accompanying drawings, forming a part of this specification, in which similar characters of reference indicate corresponding parts in both the views.

Figure 1 is a plan view of a napkin-ring, showing my design; and Fig. 2 is a cross-section of the same on the line 2 2 of Fig. 1.

The leading feature of my design consists in an open-work ornament A, extending transversely of the ring B, at the outside thereof,

with the ends of the ornament projecting beyond the edges of the ring, as plainly shown in the drawings.

20

Another feature of the design consists in the external annular beads C, arranged at the edges of the ring B and in contact with the middle portion of the ornament A, to maintain an unbroken continuity of the ring B in 25 the rear of the said middle portion of the ornament.

I claim—

A design for a napkin-ring as herein shown and described.

JOHN HASSELBRING.
